DRINKING CUP OR SIMILAR ARTICLE

Paul Davis, Beverly, Mass., assignor to Sweetheart Plastics, Inc., Wilmington, Mass., a corporation of Maryland

Filed Mar. 20, 1964, Ser. No. 79,094

Term of patent 14 years

(Cl. D44—9)

FIG.1

FIG.3

FIG. 2

FIG. 4

FIG. 1 is an elevation view of a drinking cup or similar article showing my new design;

FIG. 2 is a top plan view thereof;

FIG. 3 is a bottom plan view thereof;

FIG. 4 is a cross-sectional view taken along the section line 4—4 of FIG. 1; and

FIG. 5 is a cross-sectional view taken along the section line 5—5 of FIG. 1.

I claim:

The ornamental design for a drinking cup or similar article, as shown.
